HANDLE FOR A SCRAPING TOOL

Paul L. Marzuoli, Upper Darby, and
James B. O'Hara, Philadelphia, Pa.

Application January 30, 1947, Serial No. 136,533

Term of patent 3½ years

(Cl. D9—6)

To all whom it may concern:

Be it known that we, Paul L. Marzuoli and James B. O'Hara, both citizens of the United States and residents, respectively, of Upper Darby, in the county of Delaware and Commonwealth of Pennsylvania, and of Philadelphia, in the county of Philadelphia and Commonwealth of Pennsylvania, have invented a new, original, and ornamental Design for Handle for a Scraping Tool, of which the following is a specification, reference being had to the accompanying drawing, forming a part hereof.

In the drawing,

Figure 1 is a top plan view of a handle for a scraping tool showing our new design,

Figure 2 is a side elevation thereof,

Figure 3 is a bottom plan view thereof, and

Figure 4 is a perspective view thereof, as seen from the scraper holding end.

We claim:

The ornamental design for a handle for a scraping tool, as shown.

PAUL L. MARZUOLI.
JAMES B. O'HARA.
